UNITED STATES PATENT OFFICE.

MAURICE C. CLARK, OF PROVIDENCE, RHODE ISLAND, ASSIGNOR TO
MARVEL RUBBER COMPANY, A CORPORATION OF RHODE ISLAND.

MANUFACTURE OF RUBBER FOOTWEAR.

No. 823,925.

Specification of Letters Patent.

Patented June 19, 1906.

Application filed March 22, 1905. Serial No. 261,393.

To all whom it may concern.

Be it known that I, MAURICE C. CLARK, a citizen of the United States, and a resident of Providence, in the county of Providence and 5 State of Rhode Island, have invented a new and useful Improvement in the Manufacture of Rubber Footwear, of which the following is a full, clear, and exact description.

This invention pertains to certain novel 10 and useful improvements in the manufacture of molded footwear.

In the accompanying drawings I have shown an apparatus embodying the present invention in its preferred form; but I wish it 15 to be understood that I do not limit myself in its construction to the precise details herein shown, as there may be modification and variation without departing from the spirit or scope of the invention.

20 In the accompanying drawings all characters of reference indicate like parts in both the views.

Figure 1 is a side view of a footwear-last embodying my invention. Fig. 2 is a trans- 25 verse vertical sectional view taken through the last on approximately the line 2 2 of Fig. 1.

In the accompanying drawings I have shown a last adapted to be used in the vul- 30 canization of shoes under pressure, and the present invention pertains to a last comprising a substantially solid body portion having channels therein through which the air may be introduced between the body of the last 35 and the shoe to be vulcanized.

In the drawings the letter A designates the last as a whole, and the main portion of the same is of a shape substantially the contour of the shoe to be manufactured. In its pre- 40 ferred form such last comprises an approxi- mately solid foot portion 5, to the top portion of which is secured a solid relatively heavy plate, as at 6, a plurality of screws 7 or equivalent fastening devices securing such top 45 plate to the part 5. Extending upward from the top of the plate 6 is an extension 8, having a vertical channel 9 extending therethrough, while at the upper extremity of this extension a valve-casing 10 is provided,

50 which casing may be supplied with a valve of any suitable character. The lower end portion of the channel 9 terminates, preferably, near the upper portion of the plate 6, and diverging inclined ducts or channels 11

communicate with such channel 9 and ex- 55 tend through the plate 6 to the outside thereof and at a point below which the top of the shoe being manufactured will lie.

In employing my improved last the opera- 60 tion is substantially as follows: The shoe or boot, as at S, is built up of the usual unvul- canized material for rubber footwear upon the last, as shown in the drawings, or, if pre- 65 ferred, it may be built upon a separate last and transferred to this one. When in posi- 70 tion, the top edge s of the shoe will lie against the upper edge portion of the plate 6 and above the outer termination of the small channels 11. The last with its shoe may then be placed in the ordinary mold, which is 75 closed (not shown) and the vulcanizing heat applied and continued long enough to com- 80 plete the vulcanization. As soon as the mold is closed, air under any suitable pressure is admitted through the channel 9 and in the 85 extension 8, and thence flows through the small laterally-inclined channels 11 to the space between the inner face of the shoe and the outer surface of the last. The shoe is thus sufficiently distended by such air-pres- 90 sure to exert a proper pressure of opposition to the action of the mold to cause the com- 95 plete vulcanization of the walls of the boot or shoe interposed between such last and the 100 mold.

It will thus be seen that I have provided an exceedingly simple last for the described manner of manufacturing rubber footwear and one which will combine the essential and desired features of durability and economy. 90 It is further to be noted that instead of making the parts 5 and 6 separate they may be made out of a single solid block turned to the contour of the boot or shoe, and any means may be employed for introducing the charge 95 of air to the main vertical channel 9. With- in the reduced stem portion 10 of the exten- 100 sion 8, which forms the valve-casing, I may mount a valve of any suitable character, (not shown,) which is designed to control the pas- sage of air to the last.

What I claim is—

1. A last comprising a solid body portion over which is adapted to fit a boot or shoe, such last having a main channel extending therethrough and a branch channel commu- 105 nicating with and leading from the main channel, through which air may be passed to

the space between the surface of the last and the interior of the boot or shoe.

2. A last comprising a solid body portion adapted to fit within the boot or shoe, an extension of said body portion having a main air-channel therein, and a second channel extending from the main channel through the body portion of the last whereby air may be introduced through the main channel and 10 the second channel to the space between the last and the boot or shoe.

3. A last comprising a solid body portion provided with an extension having a main air-channel formed therein, and a second 15 channel communicating directly with said main channel and extending therefrom through the solid portion of the body for conducting air from the air-channel to the space between the solid body portion and a boot or 20 shoe surrounding the same.

4. A last comprising a body portion, an extension therefor having a fluid-channel formed therein, and a plurality of diverging channels adapted to conduct the fluid from 25 the first-mentioned fluid-channel to the space between the outer surface of the last and a boot or shoe surrounding the same.

5. A last comprising a solid body portion formed of two united sections, the upper section comprising a plate, an extension member connected to the plate and having a main channel therein, said channel having laterally-extending passage-ways connected therewith to conduct fluid from the main channel to a point outside the body portion. 30

6. A last comprising a solid body portion, and an extension member connected therewith, said extension member having a vertical channel therein for the passage-way of a fluid, and a plurality of inclined diverging 40 channels connected to the first-mentioned channel and extending through the body portion of the last, whereby fluid may be conducted from the main channel to the space between the exterior of the last and a shoe on 45 such last.

In testimony whereof I have signed my name to this specification in the presence of two subscribing witnesses.

MAURICE C. CLARK.
